UNITED STATES PATENT OFFICE.

RALPH A. METZ, OF BATON ROUGE, LOUISIANA.

APPARATUS FOR COOLING OIL OR OTHER HEATED LIQUIDS.

1,393,631.

Specification of Letters Patent. Patented Oct. 11, 1921.

Application filed February 19, 1920. Serial No. 359,951.

To all whom it may concern:

Be it known that I, RALPH ADOLPH METZ, a citizen of the United States, residing at Baton Rouge, in the parish of East Baton Rouge and State of Louisiana, have invented certain new and useful Improvements in Apparatus for Cooling Oil or other Heated Liquids; and I do hereby declare the following to be a full, clear, and exact description of the invention, such as will enable others skilled in the art to which it appertains to make and use the same.

My invention relates to improvements in apparatus for cooling oil or other heated liquids, and it is intended especially to provide an arrangement by means of which the highly heated oil coming from the stills of an oil refinery may be quickly and safely cooled; or in which the oil from a burning still may be quickly discharged from the still and quickly and safely cooled.

The dangers from fire to both life and property from leaks in stills in an oil refinery are well known, and it is a part of my present invention to lessen this danger as far as practicable.

According to my invention I provide an apparatus which is mainly immersed in a reservoir containing water, and in which the oil to be cooled may be supplied either through tubes or coils, and the cooling medium supplied interior of the tanks surrounding the coils, or in which the oil may be supplied to the interior of the tank exterior of the tubes or coils, and the cooling medium supplied to the interior of the tubes or coils.

In the normal process of cooling, it will be preferable to conduct the oil to be cooled through the tubes, while when emergency exists, or very rapid action is required, it would be preferable to conduct oil in large volume to the space in the tank surrounding the tubes, thus carrying it away quickly from the still and supplying the cooling medium through the coils as well as to the exterior of the tank, as will be hereinafter more fully described.

My invention will be more fully understood after reference to the accompanying drawings, in which like parts are indicated by similar reference symbols throughout the several views, and in which a single unit of the system is shown, it being understood that there may be a number of units similar to that hereinafter described.

Figure 1 is a plan view of one of the units, parts being broken away.

Fig. 2 shows a vertical section along the line 2—2 of Fig. 1, and looking in the direction of the arrows.

Fig. 3 shows a transverse vertical section along the line 3—3 of Fig. 1, and looking in the direction of the arrows; and

Fig. 4 is a detail showing on a larger scale the end connections of the circulating tubes, parts being broken away.

A represents a reservoir having its walls preferably made of reinforced concrete, which is preferably embedded in the ground as indicated at B. When the apparatus is in use this reservoir is preferably filled with cooling water through the pipe C controlled by the valve c, and the height of the water in the reservoir is controlled by the overflow pipe D.

It will be desirable to drain the reservoir, as, for instance, in cleaning out the same, or repairing the apparatus contained therein, and for this reason I provide a drain pipe E controlled by the foot valve f and the valve stem F and handle f'. Suitable means for supplying water to the reservoir are, of course, provided, such, for instance as either a pump, a ram, or gravity flow, and suitable means also should be provided for carrying off the water from the drain pipe E.

Mounted in the reservoir are one or more cooling tanks H, which rest upon suitable platforms, such, for instance, as the heavy I-beams G and G', which are shown as superposed and crossing each other, so that free access may be had to the bottom of the tank as desired.

The top of the tank is provided with a manhole and cover I through which access may be had to the interior of the tank, and the bottom of the tank is also provided with a manhole and cover I', the manhole constituting also a catch basin I^o for removing the residue from the bottom of the tank, as will be hereinafter described.

The bottom of the tank is preferably sloped very slightly, as at h^o, to direct the flow of any liquid therein to the catch basin I^o.

The side walls and top of the tank H may be reinforced in any convenient way, as by means of straps, preferably in the form of I-beams H^o. The heads k of the tank are reinforced by the circulating tubes or coils K, 110

whose ends are rolled or flared over, as shown at *k* in Fig. 4. These ends open into the nipples *M* which are screwed into the boiler maker's flanges *L* riveted to the plates *h*, and the other ends of these nipples are screwed into the flanged collar *m* secured to the flange *n* of the *T N*. This *T* is provided with a flange *n'* which is connected to the flange *o* of the nipple *O* connecting the *T N* to the corresponding *T N* of the adjacent tube, thus connecting one tube to the other and forming a circulating return.

The *T*'s are preferably provided with screw plugs *N*^o in line with the axis of the tube, so that the tubes may be readily rolled or removed, or repaired, if desired. I have shown the *T N* provided with a supplemental flange *n*², with bolt holes *n*³, should it be preferred to use an ordinary disk shaped cap, or blank cap and gasket, instead of the plug *N*^o.

By the herein described arrangement of tube connection, standard material may be used and it is not necessary to have parts especially made for use in any particular apparatus.

In place of the construction shown in Fig. 4 other forms of return connections may be used, such, for instance, as the well known short *L*'s, or long sweep *L*'s, which are well known in the pipe fitter's art and will not be further described herein.

The oil may be supplied either to the interior of the tubes within the tank, or to the exterior of said tubes, and simultaneously water might be supplied to the exterior of the tubes, or to the interior corresponding to the desired flow of oil. For convenience of description we will assume first that the oil is to be supplied to the interior of the tubes, and the cooling medium to the exterior of the tubes in the tank. In such case the oil is conveyed from the still or other receptacle containing the heated oil either by gravity, or by pressure, in any convenient way, not shown. This oil enters through the pipe *P* past the controlling valve *p*, and enters the series of tubes through the pipe *P'*. After passing through the series of tubes or coils in the tank, this oil escapes through the pipe *Q* and is carried off by the pipe *Q'* controlled by the valve *q*. A suction pump, not shown, should preferably be applied to the pipe *Q'* to accelerate the flow of the cooled oil.

I have shown a duplication of the circulation means for the oil just referred to, and divide the tank into two sections whereby the cooling result is secured more quickly. It will be obvious, however, that one continuous circulation device may be used instead of a duplicate set.

While the oil is following the path just indicated and is being cooled, the cooling medium, preferably raw water, it bought into the interior of the tank exterior of the coils through the water supply pipe *U*, past the

valve *u*, which is open, and into the pipe *T'* and down near the bottom of the tank, as at *T*², see Fig. 3. The water circulates around the tubes and escapes through the pipe *V*, and out through the pipe *W* controlled by the valve *w*. The water may be carried into the system either by gravity, or pumping, or otherwise, and it may be discharged into a sewer, or used for other purposes, as may be desired.

Thus I have described the flow of oil, or other liquids, through the tubes, and of the cooling medium exterior to the tubes.

In order to reverse this operation, and carry the oil or other liquid to be cooled exterior to the tubes, and the cooling medium through the tubes, I provide the arrangement that will now be described.

Oil will be carried into the system through the pipe *V'*, controlled by the valve *v*, and enters the tank through the pipe *V*, which may be provided with a supplemental valve *v'* as a further block to the flow of liquid therethrough.

After the oil has been cooled in the tank, it is carried off through pipes *T*² and *T'* (see Fig. 3) and past the valve *t'* into the pipe *T*. For this purpose the oil may be forced or sucked out, as may be preferred, and suitable pumping means are provided for that purpose.

When the oil flows in the path just indicated, the water enters through the pipes *R*, past the valves *r* into the pipes *Q*, and, flowing through the tubes or coils, it escapes through the pipes *P'* and *S*, the latter controlled by the valves *s*, and this water may be carried off to a sewer, or used for any purpose desired.

In order to completely empty the tank of oil when desired, I provide an emergency suction arrangement comprising the pipe *Y* which projects down into the catch basin *I*^o, see Fig. 3, which pipe is controlled by the valve *y* which is connected to the branch *x*² of the pipe *X'* opening into the pipe *T'*, controlled by closing off the connection with the pipe *T*², thereby blocking the suction on said pipe, or suction may be turned on to the pipe *Y*, and the residue from the bottom of the tank may be emptied out.

In order to relieve the pressure on the top of the tank when the liquid is forced in, I provide a pressure relief pipe *X*, controlled by the valve *x*, which is connected by the pipe *X'* to the pipe *T'*, and a suitable pressure gage *x*^o or safety valve, or both, may be provided, if desired, to indicate the pressure or to relieve the same automatically. Such devices are well known in the art and will not be further described herein.

In order to supply steam to the tank when required, I provide a steam main *Z*, controlled by the valves *z*, *z'* and *z*², and the condensed water in this steam main may be

blown off by the short nipple z^o , having the usual cap such as is found in use with steam heating coils. The steam is conveyed into the interior of the tank H by means 5 of the pipe Z'.

In order to relieve the steam pressure in the tank this may be accomplished either by the pipe X and its connections, or if it is desired to close the pipe X a similar result may be accomplished by having the 10 blow-off attachment V^o to the pipe V, which blow-off attachment is closed by the valve v^o.

It is desirable to admit steam into the tank before admitting the hot liquids there- 15 to, to prevent flashes, and it is also generally desirable to supply steam to the interior of the tank so as to facilitate the cleansing of the same and drive off the gases contained therein.

20 In the operation of the device for emergency work, it is preferable to admit the oil or liquid to be cooled through the pipe V' into the interior of the tank outside of the coils, and to convey the cooling medium 25 into the interior of the coils, while for ordinary usage it is preferable to carry the oil or other liquid to be cooled through the tubes or coils and to convey the cooling medium through the main body of the tank 30 exterior to the tubes or coils; the path of the liquids in each case being as hereinbefore described.

It will be obvious that various modifications might be made in the herein-described 35 apparatus, and in the construction, combination and arrangement of parts which could be used without departing from the spirit of my invention, and I do not mean to limit the invention to such details except as particularly pointed out in the claims.

40 Having thus described my invention what I claim and desire to secure by Letters Patent of the United States is:

1. Apparatus for cooling oil or other hot 45 liquid, comprising a reservoir, means for delivering water to said reservoir and for conveying it away therefrom when it reaches a predetermined level in said reservoir, with means for draining said reservoir when de- 50 sired, a closed cooling tank mounted in said reservoir and normally submerged in the water contained therein, the said tank being provided with separate passages for the flow of the hot oil and the cooling water, with 55 means for delivering the hot oil to one set of such passages, and the cooling water to the other set, substantially as described.

2. Apparatus for cooling oil or other hot 60 liquid, comprising a reservoir, means for de- livering water to said reservoir and for conveying it away therefrom when it reaches a predetermined level in said reservoir, with means for draining said reservoir when de- 65 sired, a closed cooling tank mounted in said

reservoir and normally submerged in the 65 water contained therein, the said tank being provided with separate passages for the flow of the hot oil and the cooling water, with means for delivering the hot oil to one set of such passages, and the cooling water to the 70 other set, and means for transposing the flow of oil and water, respectively, from one series of passages to the other, substantially as described.

3. Apparatus for cooling oil or other hot 75 liquid, comprising a reservoir, means for de- livering water to said reservoir and for conveying it away therefrom when it reaches a predetermined level in said reservoir, with means for draining said reservoir when de- 80 sired, a closed cooling tank mounted in said reservoir and normally submerged in the water contained therein, the said tank being provided with a series of tubes connected together in series, and connections thereto for 85 supplying either hot oil or cooling water, as may be desired, to said tubes, with means for delivering conversely either cooling water or hot oil, as may be desired, through the space in said tank surrounding said 90 tubes, substantially as described.

4. Apparatus for cooling oil or other hot 95 liquid, comprising a reservoir, means for de- livering water to said reservoir and for conveying it away therefrom when it reaches a predetermined level in said reservoir, with means for draining said reservoir when de- 100 sired, a closed cooling tank mounted in said reservoir and normally submerged in the water contained therein, the said tank being provided with a series of tubes connected together in series, and connections thereto for 105 supplying either hot oil or cooling water, as may be desired, to said tubes, with means for delivering conversely either cooling water or hot oil, as may be desired, through the space in said tank surrounding said tubes, and means for supplying steam to the 110 interior of said tank, substantially as de- scribed.

5. Apparatus for cooling oil or other hot 115 liquid, comprising a closed cooling tank pro- vided with separate passages for the flow of the hot oil and the cooling water, with means for delivering the hot oil to one set of such 120 passages, and the cooling water to the other set, and means for transposing the flow of oil and water, respectively, from one series of passages to the other, substantially as de- scribed.

6. Apparatus for cooling oil or other hot 125 liquid, comprising a closed cooling tank pro- vided with separate passages for the flow of the hot oil and the cooling water, with means for delivering the hot oil to one set of such 130 passages, and the cooling water to the other set, means for supplying steam to the interior of said tank, and means for transpos-

ing the flow of oil and water, respectively, from one series of passages to the other, substantially as described.

7. Apparatus for cooling oil or other hot liquid, comprising a closed cooling tank provided with a series of tubes connected together in series, and connections thereto for supplying either hot oil or cooling water, as may be desired, to said tubes, with means for delivering conversely either cooling water or hot oil, as may be desired, to the space in said tank surrounding said tubes, substantially as described.

8. In apparatus for cooling oil or other

hot liquid, the combination with a tank having a plurality of tubes having their opposite ends secured in the opposite heads of said tank, a double T connection and nipples connecting said tubes in series, screw plugs screwed into said T's in line with the axes of said tubes, means for supplying liquid to one end of said series of tubes, and for carrying off the liquid from the other end of said series of tubes, and means for delivering liquid to said tank to the spaces surrounding said tubes, substantially as described. 15 20 25

RALPH A. METZ.
